UNITED STATES PATENT OFFICE

2,428,027

ROTARY HOOK FOR SEWING MACHINES

Matthew G. Ivandick, Rockford, Ill., assignor to
Free Sewing Machine Co., Rockford, Ill., a cor-
poration of Illinois

Application July 22, 1944, Serial No. 546,169.

3 Claims. (Cl. 112—256)

1

This invention relates to a new and improved rotary hook for sewing machines, and has for its principal object the provision of simple and practical means for lubrication of the bobbin case rib and the raceway therefor, whereby adequate lubrication is insured over long periods of operation, without need for replenishing the supply of lubricant, and with no danger of contamination of the thread with oil.

The improvements of my invention, more specifically stated, are applied to a rotary hook constructed along the lines of that disclosed in the Southam and Wainwright Patent 2,065,349, a yieldable or floating gib ring of improved design being provided in connection with the beveled rib on the bobbin case base to form a raceway for the rib and also form a container for a circumferentially extending lubricant retaining wick, which provides sufficient storage capacity for oil without danger of excessive lubrication, the bulk of the lubricant being kept away from contact with the bobbin case rib and the raceway therefor by centrifugal action in the rotation of the thread-loop carrier, although the wick is close enough to the raceway to insure adequate lubrication more or less by capillary attraction.

In the structure of the Southam and Wainwright patent, a plurality of screws are employed to fasten the gib ring to the thread-loop carrier, and compress a number of coiled compression springs for yieldability of the ring, so as to eliminate likelihood of binding, but in accordance with my invention, I provide a plurality of spring clips, inserted between lugs on the back of the ring and the back of an annular flange on the thread-loop carrier, whereby to insure more uniform spring action and at the same time simplify the construction, make it easier to assemble, and lower the cost all around.

The invention is illustrated in the accompanying drawing, in which—

Fig. 1 is a face view of a rotary hook, embodying my invention;

Fig. 2 is a cross-section on the line 2—2 of Fig. 1;

Fig. 3 is a rear view of the rotary hook;

Fig. 4 is a side view, and

Figs. 5 and 6 are enlarged sectional details on the correspondingly numbered lines of Figs. 3 and 4, respectively.

The same reference numerals are applied to corresponding parts throughout these views.

The rotary hook shown is closely similar to that disclosed in the Southam and Wainwright patent mentioned above, and comprises a thread-

2

loop carrier 10, supporting for relative rotation a bobbin case base 11, which in turn rotatively supports a bobbin 12, retained in the base by a case 13. A hub 14 provides a means for securing the carrier 10 to the driving shaft of a sewing machine, and has a bowl shaped portion 15 integral therewith and terminating in an annular flange or rim portion 16. Received partially within the bowl shaped portion 15 is the bobbin case base 11, which is generally cylindrical and formed intermediate its ends with a circumferentially extending rib 17 that is received in an annular groove 18 formed in the inner rim portion of the bowl shaped portion 15. A gib ring 19 adapted to be secured to the flange 16 serves to retain the bobbin case base in the bowl shaped portion 15 while forming with the groove 18 a raceway for the rib 17. At 20 is indicated a spring clip secured to the bobbin case 13 by means of a screw 21, and cooperating with a tongue 22, extending radially from the case 13 to support the bobbin thread in position adjacent the path of the sewing machine needle in addition to maintaining the proper tension on the bobbin thread. A loop piercing hook 23 is provided on the rim of the bowl shaped portion 15 of the thread-loop carrier and projects forwardly in the direction of rotation of the carrier and outwardly from the carrier beyond the plane of the flange 16 to engage the thread-loop on the sewing machine needle and loop it around the bobbin thread in the usual way to form a stitch. No invention is claimed in any of the details thus far described, excepting only insofar as such details form a part of novel combinations in accordance with the present invention, as pointed out generally above, and as more specifically described hereinafter.

In accordance with my invention, the gib ring 19 is formed to provide an annular radially inwardly projecting flange 24 for abutment with the outer face of the rib 17, and to complete the raceway therefor, said flange and the rest of that section of the ring being cut away, as indicated at 25, where the hook 23 is provided on the thread-loop carrier, so as to permit projection of said hook past the plane of the ring for proper cooperation with the needle of the machine. The ring 19 is cut away at 25 through approximately 90°, as required for the proper functioning of the hook 23. Radially outwardly with respect to the annular flange 24, the ring 19 is formed to provide an annular channel or recess 26 to receive a lubricant retaining wick 27 throughout approximately 270° angularity of the ring 19. The web 28 of the channel recess has an opening 29

provided therein, so as to permit easily oiling the device without having to take it apart, that is to say, by entry of the nozzle of an oil can in the opening 29. The wick 27 will readily absorb the oil supplied in this manner, and there is, therefore, no danger of oil being left on the outside of the ring 19, or running onto the outside, assuming reasonable care and judgment is exercised in the lubrication of the machine. The opening 29, as indicated in Fig. 1, is preferably near the leading end of the channel 26 in relation to the direction of rotation of the thread-loop carrier indicated by the arrow in Fig. 1, so that there is less likelihood of any oil finding its way out of the opening 29 under centrifugal action, the bulk of the oil tending to crowd toward the other end of the recess 26, as a result of the inertia factor. Centrifugal force will insure keeping the bulk of the lubricant away from contact with the rib 17 and the raceway therefor in the rotation of the thread-loop carrier, but lubricant will find its way to the rib and raceway in sufficient amounts more or less by capillary attraction to insure sufficient lubrication. Since the lubrication is done so sparingly, it is obvious that the machine can be run for long periods without requiring oiling, and there is not much danger of contamination of the thread with oil in the operation of the machine. Capillary attraction can be relied upon in this case, because of two things: (1) the ring 19 is yieldably secured to the thread-loop carrier, as hereinafter described, and, therefore, does not engage the annular face 30, next to the groove 18, too tightly; and, (2) the wick 27 is in contact with, and therefore wets, the radially outer portion of the face 30, and there is only a relatively narrow portion of the face between the wetted portion and the groove 18 to be traversed by the oil by capillary attraction, as clearly appears in Fig. 2. The provision of the correct amount of lubricant is highly important in this portion of the machine, because of the speed of rotation, and the more or less continuous operation whenever the machine is used. Absolute freedom of movement is highly important from the standpoint of stitch formation, and to avoid likelihood of thread breakage. On the other hand, if there is not sufficient lubrication, the rib 17 and its raceway are apt to become worn excessively, and when that occurs, there is no longer obtainable the desired smoothness of operation, and the thread or lint and dirt are apt to become lodged between the relatively rotating parts and cause jamming. With the present construction all of these difficulties are avoided by reason of the fact that there is adequate storage capacity for oil in the channel 26 for operation over a long period of time, and the lubricant cannot be wasted by being thrown outwardly under centrifugal force, centrifugal force being relied upon in accordance with the present invention to retain lubricant so that it will be used only very sparingly and capillary attraction being relied upon to carry the lubricant to the parts requiring it, as previously described.

The flange 16, which is on the thread loop carrier, has a plurality of circumferentially spaced transverse grooves cut therein, as indicated at 31, one or more of which are adapted to receive indented key portions 32, formed in the peripheral wall 33 of the ring 19. The latter fits closely over the periphery of the flange 16 as clearly appears in Figs. 2 and 6, both to maintain accurate concentricity of the ring 19 with respect to

the thread carrier 10, and also avoid likelihood of oil seepage through this joint in the operation of the machine. There are three lugs 34 on the back of the ring 19, projecting radially inwardly from the inner edge of the wall 33 in register with the notches or grooves 31, so that the ring 19 can be assembled or disassembled easily by passage of these lugs through these grooves. These lugs cooperate with spring clips 35, which are inserted between the lugs 34 and the back of the flange 16 to hold the ring 19 in assembled relation to the thread-loop carrier 10, and at the same time provide the desired yield for the ring 19 in relation to the thread-loop carrier to allow enough lateral movement to prevent binding in the operation of the machine. The key projection 32 locks the ring 19 against turning with respect to the thread-loop carrier 10, and keeps the cutout portion 25 of the ring in proper relation to the hook 23 on the carrier. The spring clips 35 are generally M-shaped, as best appears in Figs. 4 and 5, whereby to provide two legs 36 for abutment with the back of the flange 16, a middle portion 37 for abutment with the lugs 34 on the ring 19, and humps 38 on opposite ends of the middle portion to engage the opposite sides of the lugs 34 to prevent accidental displacement of the clips from their assembled positions. These clips are in equally circumferentially spaced relation as shown in Fig. 3 and each has sufficient spread so that the spring tension on the ring 19 is substantially uniform throughout its circumference. Furthermore, these clips can be easily inserted in less time than is required to insert a similar number of small screws, especially when the screws have to be entered through coiled compression springs as disclosed in the Southam and Wainwright patent. A saving in time and expense is therefore realized, and the overall cost of the unit is reduced.

It is believed the foregoing description conveys a good understanding of the objects and advantages of my invention. The appended claims have been drawn with a view to covering all legitimate modifications and adaptations.

I claim:

1. In a rotary hook for sewing machines, a rotary thread-loop carrier having a loop piercing hook, a bobbin case base having a circumferential rib, a gib ring disposed on the outside of said carrier and forming therewith a raceway for the rib on said base, said carrier having an annular flange and said ring having an annular rim portion having a close working fit over the periphery of said flange to center the ring on the carrier and guide said ring for lateral movement thereon, said flange having notches provided across the periphery thereof at circumferentially spaced points, said ring having a plurality of circumferentially spaced radially inwardly projecting lugs registering with said notches and movable therethrough in the assembling of the ring on the carrier and disposed in spaced relation to the back of said flange, and spring means disposed between said lugs and the back of said flange for yieldably mounting the gib ring on said carrier for limited lateral movement.

2. A structure as set forth in claim 1, wherein said ring has at least one key projection on the rim portion thereof projecting radially inwardly, adapted to enter one of the aforesaid notches in said flange to key the ring to the carrier so as to prevent relative rotation therebetween.

3. In a rotary hook for sewing machines, a rotary thread-loop carrier having a radial flange on its periphery, the front face of which is flat and smooth and is recessed at its inner circumference to provide a beveled seat, a bobbin case base having a circumferential rib the outer face of which is flat and disposed in the plane of the flat front face of said flange and the other face of which is inclined at the same angle as the beveled seat and has bearing engagement therewith, a gib ring having a smooth surfaced flat annular portion abutting the front face of said flange and the front face of said rib to retain the bobbin case base in said carrier, said ring having an annular recess provided therein in the radially outer portion thereof containing a lubricant retaining wick disposed so as to permit lubrication by capillary attraction of the rib and the surfaces on the carrier and ring contacted thereby,

and means for resiliently securing the gib ring to said carrier.

MATTHEW G. IVANDICK.
